LIFE SAVING BOAT

Filed Nov. 16, 1928

INVENTOR
Joseph Karwoski

UNITED STATES PATENT OFFICE

JOSEPH KARWOSKI, OF WATERVLIET, NEW YORK

LIFE-SAVING BOAT

Application filed November 16, 1928. Serial No. 319,889.

This invention relates to improvements in life saving boats, and it is the principal object of my invention to provide a boat which is practically nonsinkable as it is equipped 5 with means to balance the boat in rough seas.

Another object of my invention is the provision of a boat of this character equipped with a waterproof tight closing cover or tarpaulin provided with a plurality of openings 10 for the passage of oars for the entrance and exit of passengers, and for admitting light and air to the interior of the boat.

A further object of my invention is the provision of a life saving boat of this type 15 equipped with curtains, closing the openings and windows, which can be drawn shut by means of suitable cords or the like.

A still further object of my invention is the provision of a life saving boat equipped 20 with a frame carrying the balance weight and so constructed that the upper part of said frame when not in use may be folded lengthwise to the boat, while means are provided to hold the frame in its upright position 25 for properly balancing the boat by the weight attached to the frame underneath the center of the boat, whereby this weight is so shaped as to correspond to the outline of the boat.

These and other objects and advantages of my invention will become more fully apparent as the description proceeds, and will then be specifically defined in the appended 35 claims.

In the accompanying drawing forming a material part of this disclosure:

Fig. 1 is a side elevation of a life saving boat constructed according to my invention.

Fig. 2 is a top plan view of the boat.

Fig. 3 is a fragmentary sectional end elevation thereof.

As illustrated, the body 10 of the boat is of the customary construction of the life saving boats as they are commonly used on passenger liners etc. According to my invention in the center of the boat body the same is equipped with a frame consisting of the lateral bars 11 and 12 attached at their upper ends to the gunwale of the boat by means

of the clamping bands 13, 14, held in place by screws 15 or the like.

To the upper shouldered ends of these bars are fitted the lower, correspondingly shouldered ends of uprights 16, 17, as at 18 and 19, and these uprights are pivotally connected to the bars, as at 20 while both sets of uprights and bars are held in their vertically aligned position by means of sliding sleeves 21.

The lower ends of the frame bars 11 and 12 are connected and at their point of union a balance member 22 of suitable weight determined by the size of the boat is secured, preferably curved at both sides to correspond to the boat-shape.

The uprights 16, 17 are connected at their upper ends by a cable 23, so that they may be lowered in union lengthwise to the boat if the sleeves 21 are so displaced lengthwise to 70 the uprights as to give the pivot point 20 free.

The entire boat is covered by a watertight canvas, tarpaulin or the like, generally designated 24 drawn over the hoops 25, and the lower ends are secured to the boat's gunwale by clamping bands 26, 27, united at the bow and stern of the boat by means of bolts and nuts, as indicated at 28, 29, respectively, while intermediate these points a plurality 80 of wing nuts on bolts, as indicated at 30, clamp the bands against the gunwale with the lower margin at edge of the tarpaulin clamped between them.

Suitable openings 31 in the tarpaulin allow the passage of oars 32 with which the boat may be driven, and a suitable observation opening 33 allows a free outlook towards the front of the boat, and the entrance and exit of persons, a similar opening may be 85 provided at the stern of the boat.

At suitable intervals openings or windows 34 are provided in the tarpaulin adapted to be closed tightly by means of curtains 35 adapted to be drawn shut by means of the 95 strings 36.

The operation of my device will be entirely clear from the above description by simultaneous inspection of the drawing. If it is desired to use the boat in case of accident to 100

a ship, the uprights are brought in alignment with the vertical side bars of the frame and held in this position by means of the sleeves while the tarpaulin, after all the passengers have entered the cockpit of the boat, is drawn taut and if necessary all windows and openings therein are closed by means of the curtains. The boat may then be propelled by means of the oars, and is well balanced against tilting and overturning by the weight which is properly selected to suit the size and type of the boat.

It will be understood that I have shown the preferred form of boat only and that I may make such changes in the construction as come within the scope of the claims without departure from my invention as above described.

Having thus described my invention, what I claim as new, and desire to secure by Letters Patent is:

1. In a life saving boat of the class described, a body, a frame surrounding said boat in its middle, said frame comprising a pair of lateral bars having upper shouldered ends, and united at their lower ends underneath the bottom of the boat, a balance weight on said bars at their point of union, a pair of uprights having shouldered lower ends to fit the shoulders of said bars, means for pivotally connecting bars and uprights, sleeves for holding bars and uprights in alignment in their operative position allowing a folding of the uprights lengthwise to the boat when not in use, clamps for clamping said bars to the boat's gunwale, a waterproof cover for said boat having a plurality of openings adapted to be tightly closed, and means for clamping the lower edge of said cover to the boat's gunwale.

2. In a life saving boat, a body, a pair of bars united at their lower ends under the bottom of the boat, a pair of uprights forming with said bars a frame, and united therewith, a balance weight on said bars, means for pivotally connecting bars and uprights, means for holding bars and uprights in alignment in their operative position, means for clamping said bars to the boat's gunwale, a windowed waterproof cover for said boat, means for allowing a tightly closing of said windows, and a means for clamping the lower edge of the cover to the boat.

Signed at Watervliet, in the county of Albany and State of New York this 3rd day of November, A. D. 1928.

JOSEPH KARWOSKI.
